CLAIM

The ornamental design for a triangular pouch with large spout, as shown and described.

DESCRIPTION

FIG. 1 is an elevated perspective view of a first embodiment of a triangular pouch with large spout showing my new design;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is an elevated perspective view of a second embodiment of a triangular pouch with a large spout showing my new design;

FIG. 9 is a front view thereof;

FIG. 10 is a rear view thereof;

FIG. 11 is a first side view thereof;

FIG. 12 is a second side view thereof;

FIG. 13 is a top view thereof; and,

FIG. 14 is a bottom view thereof.

The broken lines shown in FIGS. 4-5, 7-8, and 11-14 are for illustrative purposes only and form no part of the claimed design.
